MACHINE GUN

Smith B. Howe, Grand Island, N. Y., assignor to
Bell Aircraft Corporation, Buffalo, N. Y.

Application August 9, 1941, Serial No. 406,154

10 Claims.

(Cl. 89—33)

This invention relates to rapid fire guns, and more particularly to improvements in means for feeding ammunition thereto.

One of the objects of the invention is to provide an improved device for guiding movement of a cartridge belt from a magazine toward an associated machine gun or the like. Another object of the invention is to provide a device for controlling the movement of a cartridge belt from a magazine towards a machine gun disposed below the magazine, in an improved manner. Another object of the invention is to provide a device of the character described which is adapted to prevent unintended siphoning of a cartridge belt out of its magazine, in an improved manner. Another object of the invention is to provide an improved device of the character described which is adapted to function in conjunction with flexibly mounted guns in an improved manner. Other objects and advantages of the invention will appear from the specification hereinafter.

In the drawings:

Fig. 1 is a diagrammatic elevation of a magazine and gun battery arrangement of the invention;

Fig. 2 is an enlarged view of the cartridge belt movement control device of Fig. 1;

Fig. 3 is an end elevation of the mechanism of Fig. 2; and

Fig. 4 is a fragmentary section taken substantially along line IV—IV of Fig. 2.

The drawings illustrate the invention in conjunction with a machine gun designated in rear view at 10, which it will be understood may be of any desired type and is arranged to be flexibly mounted relative to some suitable base support by means of the usual swivel yoke device designated at 12 (Fig. 1). The magazine for containing a suitable supply of cartridges for the gun 10 is designated at 14, and a belt of cartridges is indicated at 15 as being trained over rollers 16—17 carried by the magazine 14 for ease of belt feeding movement out of the magazine toward the gun. The gun 10 is similarly provided with a cartridge belt guiding roller 18 which is rotatably carried by a bracket 19 extending rigidly from the gun structure, so that the cartridge belt 15 is thereby guided to move smoothly into registry with the cartridge feed-way port of the gun 10 from the region of the magazine thereabove.

A cartridge belt control mechanism designated generally at 20 is mounted upon some suitable stationary supporting structure as designated at 22, at a position intermediately of the gun 10 and

the magazine 14; it being understood that the gun and magazine and cartridge belt control device will be mounted as a unit upon any desired supporting mechanism such as a tank or airplane or other vehicle or stationary fort or the like. Thus, the general relative arrangement of the gun and the magazine and the belt control device will remain the same under all service conditions, and it will be understood that the organization and relative arrangement of the operative elements of the gun battery unit as illustrated and described will be of particular use wherever it is advantageous to locate the gun within the lower portion of the mounting vehicle or other supporting structure and below the ammunition magazine, as in the case of a belly turret of an airplane or the like.

The cartridge belt movement control device 20 includes a mounting shaft 24 which extends laterally from the device for rotational mounting within a suitably bored portion of the stationary support 22, so that the control device 20 may be free to rotate about an axis extending longitudinally of the shaft 24. The shaft 24 is grooved as at 26 to register with a locking screw 27 which is threaded into the stationary support 22 so as to engage the grooved portion 26 of the shaft whereby to prevent accidental displacement of the control device 20 from its mounting support without interfering with free rotation thereof about the axis of the shaft 24. The shaft portion 24 carries at its outer end and integrally therewith a back plate portion 28 (Figs. 2—4) which extends transversely of the shaft 24. Spaced parallel arm portions 29 extend forwardly from the back plate portion 28 at opposite sides thereof to thus provide in effect a U-shaped bracket; the arm portions 29—29 being fixed to the back plate portion 28 by means of machine screws 30.

A driven roller 32 formed with axially spaced sprocket portions 33—34 is keyed to a shaft 35 which extends at opposite ends of the roller 32 into bearing engagement with suitably apertured portions of the opposite side plates 29, for rotatably mounting the roller 32 upon the side plates 29—29. The roller 32 is keyed to the shaft 35 as at 36. The sprocket portions 33—34 of the roller are formed of different dimensions so as to adapt them to engage the corresponding opposite end portions of the cartridges forming the cartridge belt 15 in geared relation as the belt moves from the magazine through the control device 20 toward the gun 10. A freely rotatable roller 38 is mounted in spaced opposed relation with respect to the sprocket roller 32 by

means of a shaft 39 extending in bearing relation through opposite portions of the side plate members 29-29. Thus, the roller 38 is adapted to maintain the cartridge belt 15 in geared connection relation with respect to the sprocket roller 32 at all times.

A cartridge belt deflecting plate 42 is mounted upon each of the side arm portions 29-29 to guide the opposite end portions of the cartridges of the cartridge belt 15 as it passes through the control device 20 between the positions of the sprocket roller 32 and the idler roller 38. Preferably, the deflector plates 42 will be curved at their inner surface portions as illustrated to provide smooth guiding action with respect to the cartridge belt.

At its opposite end portions the sprocket roller shaft 35 is extended beyond the corresponding side plate portions 29-29 so as to carry thereon a pair of friction drums 44-44. The drums 44-44 are pinned to the shaft 35 as at 45 (Fig. 4), and thus upon movement of the cartridge belt 15 through the control device 20 the geared engagement of the cartridge belt with the sprocket roller 32 causes the drums 44-44 to rotate. A friction band 46 is arranged adjacent the periphery of each of the drums 44-44 for releasable frictional engagement therewith. The bands 46-46 are similarly mounted at corresponding end portions upon pins 48-48 extending from the bracket portion of the device, and are locked thereon by cotter pins 49-49. At their opposite ends the bands 46-46 are similarly mounted by means of pins 50-50 extending transversely through opposite side wall portions 52-52 of a bell crank member 54 which is pivotally hung upon corresponding extending opposite end portions 56 of the shaft 39. Thus, the bell cranks 54-54 are free to oscillate about the axis of the shaft 39 to alternately increase and decrease the degree of frictional engagement between the bands 46-46 and the corresponding drums 44-44.

A lever 60 is freely pivoted upon each extending end portion 56 of the shaft 39 between the positions of the spaced side wall portions 52-52 of the corresponding bell crank members, and the levers 60-60 are arranged to extend downwardly between corresponding spaced abutment portions 62-64 of each of the bell cranks 54-54, and to carry at their lower ends a transverse shaft 66 upon which is rotatably mounted an idler roller 68 so formed as to be adapted to rotatably engage the cartridge belt 15 as it moves through the control device. Deflector discs 69 are preferably carried at opposite ends of the roller 68 to smoothly guide the cartridges of the cartridge belt 15 as it passes through the device.

The abutment portions 62-64 of the bell crank members 54-54 are so relatively positioned and the levers 60-60 are so formed and arranged as to dispose the idler roller 68 substantially in line with the sprocket roller 32 and the gun guide roller 18 when the cartridge belt 15 is taut between the positions of the sprocket 32 and the guide roll 18; and the friction bands 46-46 are so arranged that under such conditions there is no substantial frictional engagement between the bands and the drums 44-44. However, it will be understood that upon slackening of that portion of the cartridge belt which extends between the positions of the sprocket roller 32 and the gun guide roll 18, the idler roller 68 and its supporting lever mechanism will be

thereby freed to pivot downwardly under the influences of gravity in such manner as to rotate the bell crank members 54-54 counterclockwise as viewed in Figs. 1 and 2. Thus, the bands 46-46 are caused to be tightened against the drums 44-44 to provide frictional resistance to relative movement therebetween. Therefore, in response to any slackening of the belt between the positions of the control device 20 and the gun 10, the control device 20 will automatically operate to slacken the speed of belt movement through the control device 20 until such time as the gun operation requires an increase of cartridge belt feeding speed, whereupon the cartridge belt will tighten and actuate the bell crank roller 68 to elevated or frictional release position whereby the cartridge belt 15 will be freed to move at increased speed downwardly from the magazine into the gun. Thus, the control device 20 automatically functions to control the cartridge belt in complete accord with the feeding requirements of the gun.

Coil springs 70-70 are preferably mounted in connection with each of the levers 60-60 for assisting the operation of the forces of gravity in connection with actuation of the bell cranks 54-54 to friction-band tightening condition. As illustrated in Figs. 2 to 4, the coil springs 70 are provided with looped end portions 72 engaging about pins 74 extending from corresponding of the side plate members 29-29, and from thence the spring members engage at their looped central portions about the shaft 39, and terminate at their opposite ends in turned finger portions arranged to abut against the corresponding levers 60-60 below the shaft 39, as illustrated in Fig. 2. Thus, the springs 70-70 operate at all times to urge the levers 60-60 to rotate about the shaft 39 in a counterclockwise direction as viewed in Fig. 2, for tightening of the friction bands 46-46 against the drums 44-44. It will be understood that the springs 70-70 will be so arranged as to provide such action as will be required to cause the control device 20 to brake the movement of the cartridge belt 15 out of the magazine 14 in accord with the purpose of the invention as explained hereinabove, and that the springs 70-70 will be adapted to be overcome by the forces imposed upon the idler roller 68 upon tightening of the cartridge belt 15, for release of the mechanism braking action.

The abutment portions 62-64 of the respective bell crank members 54-54 are relatively spaced so as to engage the corresponding lever members 60 loosely in the manner of lost-motion connection device, and a set screw 75 is threaded to extend through each of the abutment portions 64-64 to engage at their inner ends against corresponding of the levers 60-60 for altering the angular dispositions of the corresponding bell crank and lever members and to regulate the amount of lost motion space therebetween. Thus, it will be understood that adjustments may be readily made of the timing of initial movements of the levers 60 relative to the bell cranks 54 in connection with the cartridge belt regulating operation of the mechanism, whereby fine adjustments of the operation of the mechanism may be provided to suit different conditions of operation.

It will be appreciated that a particularly important feature and advantage of the invention resides in the fact that the control device 20 is freely rotatable as a unit about the axis of its mounting shaft 24, whereby as the gun 10 is swiveled relative to its supporting base in con-

nection with the usual elevational and azimuthal adjustments of the gun during firing thereof, the twists imposed upon the cartridge belt 15 between the positions of the gun and the ammunition magazine will be divided between the portions of the cartridge belt above and below the control device 20. Thus, acute turns and twists in the cartridge belt are avoided, and a smoother and otherwise improved feeding operation of the cartridge belt to the gun under all conditions is assured.

Although only one form of the invention has been illustrated and described hereinabove, it will be understood that the invention is not so limited but that various changes may be made therein without departing from the spirit of the invention or the scope of the appended claims.

I claim:

1. A cartridge belt feed control device including a support, a pair of positionally fixed cartridge belt rollers mounted upon said support and arranged in spaced substantially vertical alignment, a gear roller mounted upon said support and disposed intermediately of said spaced rollers and laterally offset from the vertical alignment thereof and having toothed portions for engaging a cartridge belt when trained between said spaced rollers and against said gear roller in geared relation therewith whereby movement of said cartridge belt between the positions of said spaced rollers causes said gear roller to rotate, braking means operatively associated with said gear roller, an idler roller pivotally mounted upon said support adjacent said cartridge belt so as to be moved thereby during tightening and slackening movements thereof, and means connecting said idler roller and said brake means for releasing the latter upon tightening of said cartridge belt and for actuating said brake means to braking condition upon slackening of said cartridge belt.

2. A cartridge belt feed control device including a support, a pair of positionally fixed cartridge belt rollers mounted upon said support, a sprocket mounted upon said support and disposed intermediately of said spaced rollers and having toothed portions thereof for engaging a cartridge belt when trained between said spaced rollers in geared relation therewith whereby movement of said cartridge belt between the positions of said spaced rollers will cause said sprocket to rotate, braking means operatively associated with said sprocket, an idler roller movably mounted upon said support adjacent said cartridge belt so as to be moved thereby upon tightening and slackening thereof, and means connecting said idler and said brake means for releasing the latter upon tightening of said cartridge belt and for actuating said brake means to braking condition upon slackening of said cartridge belt.

3. In combination, a magazine, a cartridge belt training from said magazine to a position therebelow, a cartridge belt feed control device including a pair of positionally fixed cartridge belt rollers arranged in spaced vertical alignment and engaging said cartridge belt at positions below said magazine, a sprocket disposed intermediately of said spaced rollers and in laterally offset relation to the vertical alignment thereof and having toothed portions engaging said cartridge belt in geared relation therewith whereby movement of said cartridge belt out of said magazine causes said sprocket to rotate, braking means operatively associated with said

sprocket, an idler roller movably mounted against said cartridge belt so as to be moved thereby during tightening and slackening movements thereof, and means connecting said idler roller and said brake means for releasing the latter upon tightening of said cartridge belt and for actuating said brake means to braking condition upon slackening of said cartridge belt.

4. In combination, a gun, a cartridge belt feeding into said gun, and a cartridge belt feed control device including a sprocket spaced from said gun and having toothed portions engaging said cartridge belt in geared relation therewith whereby movement of said cartridge belt towards said gun causes said sprocket to rotate, braking means operatively associated with said sprocket, an idler roller movably mounted adjacent said cartridge belt so as to move therewith during tightening and slackening movements thereof between the positions of said sprocket and said gun, and means connecting said idler roller and said brake means for releasing the latter upon tightening of said cartridge belt and for actuating said brake means to braking condition upon slackening of said cartridge belt.

5. In combination, a gun, a cartridge belt feeding into said gun, and a cartridge belt feed control device including a sprocket spaced from said gun and having toothed portions engaging said cartridge belt in geared relation therewith whereby movement of said cartridge belt towards said gun causes said sprocket to rotate, brake band means operatively associated with said sprocket, an idler roller pivotally suspended below said sprocket adjacent said cartridge belt so as to move therewith during tightening and slackening movements thereof between the positions of said sprocket and said gun, and lever means connecting said idler roller and said brake band means for releasing the latter upon tightening of said cartridge belt and for actuating said brake band means to braking condition upon slackening of said cartridge belt.

6. In combination, a gun mounted upon a support, a cartridge belt feeding into said gun, and a belt feed control device including a bracket pivotally mounted upon said support at a position spaced from said gun, a sprocket rotatably mounted upon said bracket and having toothed portions engaging said cartridge belt in geared relation therewith whereby movement of said cartridge belt towards said gun is synchronized with rotation of said sprocket, brake band means operatively associated with said sprocket, an idler roller pivotally mounted upon said bracket and engaging said cartridge belt between the positions of said sprocket and said gun, and lever means connecting said idler roller and said brake band means for releasing the latter upon tightening of said cartridge belt and for actuating said brake band means to braking condition upon slackening of said cartridge belt.

7. In combination, a gun mounted upon a support, a cartridge belt feeding into said gun, and a belt feed control device including a bracket pivotally mounted upon said support at a position spaced from said gun, a sprocket rotatably mounted upon said bracket and having toothed portions engaging said cartridge belt in geared relation therewith whereby movement of said cartridge belt towards said gun is synchronized with rotation of said sprocket, brake band means operatively associated with said sprocket, lever means pivotally mounted upon said bracket, an

idler roller carried by said lever and engaging said cartridge belt between the positions of said sprocket and said gun, said lever means connecting said idler roller and said brake band means for releasing the latter upon tightening of said cartridge belt and for actuating said brake band means to braking condition upon slackening of said cartridge belt.

8. In combination, a gun mounted upon a support, a cartridge belt feeding into said gun, and a belt feed control device including a bracket pivotally mounted upon said support at a position spaced from said gun, a sprocket rotatably mounted upon said bracket and having toothed portions engaging said cartridge belt in geared relation therewith whereby movement of said cartridge belt towards said gun is synchronized with rotation of said sprocket, brake band means operatively associated with said sprocket, an idler roller pivotally mounted upon said bracket and engaging said cartridge belt between the positions of said sprocket and said gun, lever means connecting said idler roller and said brake band means for releasing the latter upon tightening of said cartridge belt and for actuating said brake band means to braking condition upon slackening of said cartridge belt, and spring means associated with said lever means for urging the latter to move said idler roller against said cartridge belt.

9. In combination, a machine gun, an ammunition magazine spaced from said machine gun, a cartridge belt training from said magazine into said machine gun in response to pulling forces thereon and normally tautened by said pulling forces, a control member geared to said cartridge belt at a position intermediately of said magazine and said gun and adapted to be moved in

accord with movement of said cartridge belt from said magazine, brake means associated with said control member, idler means adapted to bear against said cartridge belt, and lever means connected to said brake means and said idler means and adapted to be actuated by the latter upon slackening of said cartridge belt to brake the movement of said control member whereby to brake the movement of said cartridge belt from said magazine toward said gun, said lever means comprising a pair of members connected respectively to said idler means and said brake means and interconnected by means of a lost motion connection device to provide regulated response to alternate tightening and slackening of said cartridge belt.

10. In combination, a machine gun, an ammunition magazine spaced from said machine gun, a cartridge belt training from said magazine into said machine gun in response to pulling forces thereon and normally tautened by said pulling forces, a sprocket member geared to said cartridge belt at a position intermediately of said magazine and said gun and adapted to be rotated in accord with movement of said cartridge belt from said magazine, brake band means associated with said sprocket, idler means bearing against said cartridge belt, and lever means comprising a lost motion connection between said idler means and said brake band means and adapted to be laggingly actuated upon alternate slackening and tightening of said cartridge belt to brake the movement of said sprocket member and to release the latter whereby to control the movement of said cartridge belt from said magazine toward said gun.

SMITH B. HOWE.
